OSCILLATING MOTOR FAN

Werner Räthel, Berlin-Neukolln, Germany, assignor to Reiss & Klemm, Berlin, Germany, a firm of Germany

Application December 12, 1932, Serial No. 646,900
In Germany May 9, 1932

2 Claims. (Cl. 230—256)

It is known that the oscillating effect of a fan can be produced by a crank gearing coupled with the motor of the fan. In most constructions of this kind hitherto known the crank is linked to a rigidly fixed pin outside the motor casing and together with the oscillating arm visible from the outside. It is true that thus a simple gearing between the fan shaft and the crank becomes possible, but there is the disadvantage that such gearing must be located in a separate casing and that, when incautiously handled, the oscillating arm of the crank is exposed to injury and thus easily distorted. Such distortion provokes interruption of the working. Besides the separate casing increases the cost of manufacture and also as well as the oscillating arm arranged outside the casing affects the ornamental appearance of the fan, especially in small, elegant table fans.

Moreover the bearings for the gearing and the crank in the constructions hitherto known require a particular shape of the motor casing, so that standard casings cannot be employed. For this reason it is not possible subsequently to mount in a fan without oscillating movement a device changing such fan into one of the oscillating type.

Said difficulties are overcome by the present invention which is likewise based on the known construction of a fan that oscillates by means of a crank driven by the fan motor and linked to a stationary pin.

According to the invention the crank pin is inside the motor casing and is linked to a stationary pin, which latter is outside the casing rigidly fixed to the base and extends into the interior of the casing through a slot shaped in accordance with the oscillating movement.

The arrangement of the gearing, the oscillating arm and the crank inside the motor casing require, if subsequent insertion of the oscillating mechanism is desired, further measures of a special kind which can be best illustrated by the following drawings.

In the accompanying drawings Figures 1-6 illustrate the invention.

Fig. 1 shows a view partly in section,

Figs. 2 and 3 the crank gearing and its bearing in combination with a disengaging device,

Fig. 4 the disengaging device alone,

Fig. 5 the fastening of the guard cage of the fan to the casing,

Fig. 6 is a vertical section of the device through the plane of the motor shaft.

According to Fig. 1 the fan consists of the base or column 1, above which the motor casing 2 inclusive of the propellers 3 and the guard cage 4

are arranged oscillating around the vertical axis of the column 1. The motor of usual construction has the bracket 5, which contains the bearings for the motor shaft 14. The bracket 5 supports a frame for the gearing. For this purpose the threaded holes 6 and 7 are bored in that portion of the bracket 5 seen in Fig. 1, which contains the bearing 8. The motor shaft extends through the bearing 8 and is threaded at the projecting portion.

Between the base 1 and the motor casing 2 there is, rigidly secured to the base, plate 11, to which an equally stationary pin 10 is secured. This latter projects through the segmental slot 12 into the motor casing and forms with its upper end 70 the stationary fulcrum of an oscillating link 13 connected with an arm of the crank 26 (Figure 6). The segmental slot 12 is concentric with the vertical rotating axis of the motor casing. The slot therefore permits the oscillating movement of the casing. The crank linked to the oscillating arm 13 is together with its gearing arranged on a separate frame 15 (Fig. 2). The frame 15 has two bearings 16 for supporting a shaft 17, to which a worm wheel 18 is fastened. After the insertion 80 of the frame 15 the worm wheel is in mesh with the motor shaft 14 as shown in Fig. 2 and Fig. 3.

The shaft 17 carries at its lower end a spur gear 23, which is in mesh with the larger spur gear 24. The spur gear 24 is secured to the shaft of the crank 25, which is supported by a bifurcated portion 31 of the frame 15. The crank 26 is secured to the lower end of the shaft 25, and the crank pin 27 is eccentrically fastened to the crank. The oscillating arm 13 is linked to the pin 27, the other end of which, provided with a hole, is, when the frame 15 is being inserted, set upon the pin 10 (Fig. 6).

The frame 15 has an oblong opening 19 (Fig. 2) of such a size that the bearing 8 of the motor shaft can pass through when the frame is inserted. Besides the frame 15 is provided with two smaller oblong holes 20 and 21, which correspond with the threaded holes 6 and 7 of the motor bracket 5. Now two threaded pins are screwed through the openings 20 and 21 in the holes 6 and 7, not far enough, however, to press the heads of the threaded pins on the frame 15 of the motor bracket 5. On the contrary, there remains a clearance sufficient for the movement of the frame 15 in the direction of the arrows 22. The frame 15 is during its movement further guided by the slide-bars 28, which are arranged above and below at the motor bracket 5.

The movement of the frame 15 in the sense of 110

the arrows 22 engages the worm wheel 18 with the motor shaft 14 or disengages it from said motor shaft. The disengaging device required for this is particularly marked in Fig. 4, while Fig. 5 3 shows the frame in cooperation with the disengaging device, both parts seen from above.

The frame 15 has two stops 29 and 30. Against the stop 29 presses the pin-like end 38 of a lever provided with the handle 35, which lever is guided in the slantwise cut bush 37 secured to the frame 32 (Figs. 3 and 4). To the pin 38 is secured a projecting piece 36, which at the rotation of the pin around its axis slides along the oblique surface of the bush 37 and thus effects a forward movement of the pin 38. The forward movement communicates itself to the frame 15, which in this way is likewise moved forward, by which movement the worm-wheel 18 is disengaged from the motor shaft 14. During this movement a spring 47 (Fig. 3) acts upon the crank frame against the forward pressure of the pin 38.

When the worm-wheel 18 is to be engaged again with the motor shaft, the handle 35 is to be turned in the opposite direction. The spring 47, which was put under tension during the forward movement, leads the frame 15 back to its original position, by which the worm-wheel 18 is again put in mesh with the shaft 14.

The degree of coupling (respectively the final position of the back movement) is regulated by the adjusting screw 34, that touches the stop 30 of the frame 15. Such adjusting screw 34 is supported by the frame 32, which with its hole 33 (Fig. 4) is set upon one of the brush holders 9 (Fig. 1) and is here secured with nuts 39 (Fig. 3). The spring 47 is placed on the second brush holder and also secured between two nuts.

The construction of the oscillating mechanism and the motor is clearly shown in Fig. 6, and in this figure are also shown the commutator 58 and the brush holders 9, which are shown in detail in Fig. 3. Fig. 6 also shows in detail the means for mounting the motor and casing on the base 1. The motor and its mounting are well known in the art and, specifically, form no part of the present invention.

The frame 5 of the motor is rigidly secured to the stator iron 48. Angular supports 49 and 50 are secured to the stator iron. The angular support 49 is secured by the screw 51 to the casing 2 which has the closing cap 2a. The angular support 50 has a bore with internal thread wherein a tube 52 is screwed. For this purpose, the tube 52 is provided on the upper part with an outer thread 53. The casing 2 is provided at a suitable place with a bore through which the tube 52 is inserted. When the tube 52 is screwed into the bore, a collar 54 of the tube 52 presses the casing 2 against the angular member 50.

The tube 52 is now adapted to be rotated in a vertical position in the base column 2. For this purpose, the base column is hollow and bored upwardly in the vertical central axis. A guide bushing 56 fits tightly in the bore. The upper edge of the said bushing engages over the plate 11 on which the stationary pin 10 for the oscillating arm 13 is mounted and securely riveted.

The plate 11 is thus rigidly secured to the column 1 and the guiding bush 56. The latter guides the tube 52. A spring washer 55 is interposed between the upper edge of the guiding bush 56 and the collar 54 of the tube 52. The tube 52 is also provided on the lower part with an outer thread 59 whereon a nut 57 may be screwed. By tightening the said nut, the casing 2 is secured against the base column and the pressure of the spring washer 55, which is exerted during the oscillating movement, is adjusted.

Finally, it is obvious from Figure 6 that the left end of the motor shaft 14 has screw threads 14a which are adapted to engage with the worm wheel 18 (Fig. 2).

To permit the use of standard casings without additional working, the guard cage of the fan is fastened in a very suitable way. Fig. 5, showing a section through the empty motor casing (without hood), illustrates this kind of fastening.

The motor casing 2 is at the left side reduced in the customary way. The reduced portion 43 supports a circular clip 40, slit in one place, with two flanges 44 at the slit. The flanges 44 are provided with holes, one of which is threaded for receiving the set-screw 41. The clip 40 is by screwing a nut on the bolt 41 pressed on the reduced portion 43. Along the circumference of the clip 40 there are in adequate distances short portions 42 of the clip 40 pressed out to form plain pedestals, through which the ends 45 of the struts 4, which are bent over, are passed. Such ends are soldered up in the portions 42 in such a way that before mounting the clip 40 the soldering mass is poured from the inside in the 110 openings 46, which have been produced by the pressing-out of the portions 42.

What I claim as new and desire to secure by Letters Patent of the United States, is:

1. In an electric oscillating fan the combination of a motor driving said fan, a gearing, a crank, an oscillating arm and a stationary pin, said gearing connecting said crank with the shaft of said motor, said crank being connected with said stationary pin by said oscillating arm, said gearing, said crank and said oscillating arm being completely enclosed in the casing of said motor, said casing being provided with a slot, said stationary pin extending through said slot into the interior of said casing, and said oscillating arm being linked to that part of said stationary pin which extends into the interior of said casing.

2. In an electric oscillating fan, the combination with a base support for the fan, with a casing provided with a vertical pivot journaled in the upper end of the base support and having in its bottom a segmental slot concentric to the pivot, a vertical pin fixed on the base support and extending through the segmental slot into the casing, a motor mounted within the casing for driving the fan, gearing enclosed within the casing and driven by the motor, said gearing including a rotatable crank, and a link within the casing connecting the crank with the fixed pin so that rotation of the crank oscillates the casing on its vertical pivot.
